UNITED STATES PATENT OFFICE.

CHARLES K. ERNST, OF BUFFALO, NEW YORK.

HOISTING APPARATUS.

1,013,005.

Specification of Letters Patent. Patented Dec. 26, 1911.

Application filed March 13, 1911. Serial No. 613,985.

To all whom it may concern:

Be it known that I, CHARLES K. ERNST, a citizen of the United States, residing at Buffalo, in the county of Erie and State of New York, have invented a new and useful Improvement in Hoisting Apparatus, of which the following is a specification.

This invention relates to improvements in hoisting apparatus of that kind which is intended more particularly to be used in hoisting ashes and other material from a cellar or vault to the side-walk or floor above the same.

The object of this invention is to provide an apparatus of this kind which will be simple and inexpensive in construction, which can be easily installed in the vault or cellar and will occupy comparatively small space therein, which, when not in use, stands concealed beneath the side-walk or floor where it is out of the way, and which can be easily raised to a hoisting position in which it projects above the side-walk and in this position can be readily operated for raising articles from and lowering them into the cellar.

In the accompanying drawings, consisting of two sheets: Figure 1 is a side elevation of a hoisting apparatus embodying the invention, showing the same in its lowered position. Fig. 2 is a similar view of the apparatus in its hoisting position. Fig. 3 is a fragmentary front elevation thereof. Fig. 4 is a fragmentary sectional elevation, on an enlarged scale, of the apparatus as shown in Fig. 1. Fig. 5 is a top plan view of the apparatus. Fig. 6 is a cross-section thereof in line 6—6, Fig. 4. Fig. 7 is a fragmentary front elevation, partly in section, of the upper portion of the apparatus when in its lowered position. Fig. 8 is a similar view, when the apparatus is in its hoisting position.

Like reference characters refer to like parts in the several figures.

The hoisting apparatus comprises an upright supporting member A which is secured in the vault or cellar beneath the opening in the side-walk or floor, and a hoisting member B which is slidably mounted on the support A and can be elevated to project

up through the opening and form a hoist for raising articles through the same onto the side-walk. The support A is of channel-shape having a central web portion *a* and parallel edge flanges *a'* *a'*, and the hoisting member is of T-shape and is arranged within the channel portion of the support A with its oppositely extending flanges in engagement with the inner face of the web *a* and its central flange projecting outwardly away from this web.

The hoisting member B preferably consists of two angle bars which extend parallel with each other and are secured together in such a manner as to form oppositely extending flanges *b* *b* which engage the web *a*, and parallel flanges *b'* *b'* which project outwardly therefrom and are spaced apart so as to leave a continuous open slot or channel between them which extends longitudinally of the member B throughout its length. The angle bars may be secured together in any suitable manner, as by a series of bolts *b*² which connect the flanges *b'* *b'* and have 75 spacing sleeves *b*³ which are arranged on the bolts between the flanges and retain the bars in their spaced position.

The hoisting member B is adapted to be moved endwise of the supporting member A and for the purpose of retaining it in sliding engagement therewith, the supporting member is provided near its upper end with suitable guide-ways *c* *c* in which the flanges *b* *b* of the member B are adapted to travel. 80 These guide-ways may be formed in any suitable manner. In the construction shown, angle irons C C are employed for this purpose, each being riveted or otherwise suitably secured at one flange to the inner side 85 of one of the edge flanges *a'* with its other flange spaced a sufficient distance from the web *a* to admit one of the flanges *b* and form a guide therefor.

The supporting member A stands in an upright position in the cellar and is preferably secured in such position so that it can turn freely in a horizontal direction. Any suitable means may be employed for this purpose. That shown comprises a base 100 plate D upon which the support A rests and with which it has pivotal connection by

means of a depending post *d* which engages in a hole in the base plate, and a hinge *D'* of usual construction which connects the upper end of the support *A* to the side-wall 5 of the cellar, being preferably bolted or riveted to the frame which surrounds the door or opening therein. This permits the hoisting member which is carried by the supporting member to be turned in a horizontal direction in both its raised and lowered positions and prevents any undue strain and stress which would otherwise fall on the supporting member if the hoisting member could be turned independently thereof.

15 Any suitable means may be employed for elevating the hoisting member to its hoisting position and returning it to its lowered or telescoping position. In the construction shown, a rope or cable *E* is provided which 20 is secured at one end to the lower end of the hoisting member, preferably to the lowermost spacing sleeve *b*³, and extends upwardly in the open space between the flanges *b' b'* to a pulley *e* which is suitably journaled in an opening in the web *a* near the upper end thereof. The rope *E* passes over this pulley and downwardly at the rear of the supporting member *A* and over suitable intermediate swivel pulleys *e'* and *e''* to a 25 winding drum *e*³ which is journaled in a frame or support *F* which stands on the floor adjacent to the base plate *D* and which is adapted to be turned for winding the rope *E* thereon for raising the hoisting member 30 to its elevated position, as shown in Fig. 2, having for this purpose an end extension 35 for a crank handle and the usual ratchet to prevent its unwinding.

The supporting member *A* has suspended 40 therefrom a pin *G* and its side flanges *a' a'* are provided near their upper ends with holes or openings *g* through which this pin is adapted to extend. When the hoisting member has been raised by means of the 45 rope *E* and winding drum *e*³ to its elevated position, the pin *G* is inserted in the holes *g* so that it bridges the space between the flanges *a' a'* beneath the lower end of the hoisting member and forms a stop or support 50 for the hoisting member, as shown in Fig. 8. This relieves the elevating rope and its drum from the weight and strain to which the hoisting member is subjected when in use and brings the same directly 55 upon the supporting member, which is sufficiently strong to withstand it. The open longitudinal slot or opening between the flanges *b' b'* of the hoisting member permits the rope *E* to travel freely therein and 60 to pass over the pulley *e* without interference as the hoisting member is being raised and lowered, while at the same time the engaging faces of the members *A* and *B* can

be made to fit snugly together throughout their length.

65 The hoisting member is provided at its upper end with a laterally extending arm *H* which is preferably formed of two parallel angle bars *h h* which are connected together by bolts *h' h'* in such a manner 70 as to leave a longitudinal slot or opening between them, and are secured at their inner ends by bracket plates *h*² to the upper ends of the spaced angle bars which form the hoisting member. In the slot or space between the angle bars *h*, at the outer end of the arm, is journaled a pulley *i* over which passes a hoisting rope or cable *I*, one end of which depends therefrom and has a suitable attaching device *i'* for securing it to the 80 ash cans or other articles to be raised. The other end of the hoisting rope passes from the pulley *i* over a pulley *i''* journaled in the bracket plates *h*² at the junction of the arm *H* with the hoisting member, thence 85 downwardly at the front of the hoisting and supporting members and over intermediate swivel pulleys *i*³ and *i*⁴ on the base plate *D* and the frame *F*, to a winding drum *K* which is journaled in the frame *F*. The 90 winding drum *K* has, at one end, the usual extension to which a crank handle can be fitted for turning the same, and at its other end is geared to an auxiliary shaft *L* which is journaled in the frame *F* and can be 95 turned for rotating the drum. When the hoisting rope carries but a medium weight, it can be easily raised by applying the power directly to the winding drum for rotating the latter. When the weight is a heavy one, 100 the power is applied to the auxiliary shaft *L* which by reason of its gear connection with the winding drum increases the leverage thereon and enables the weight to be easily hoisted.

105 While the described construction and arrangement of the winding and hoisting means has been found to be a simple and efficient one, any other suitable means may be employed for this purpose and arranged 110 on the hoisting apparatus and operated in any desirable manner.

The entire construction is a very simple and inexpensive one. The supporting and hoisting members are formed from angle and channel bars of standard shapes and sizes and no specially rolled or formed bars are required for this purpose. The longitudinal slots between the angle bars which form the hoisting member and its lateral 120 arm form a space in which can be placed the elevating and hoisting ropes and the pulleys over which these ropes travel, thus greatly simplifying and strengthening the construction. The apparatus can be readily 125 installed at little expense and occupies but

a small amount of space in the cellar. The hoisting member can be turned in its raised position to swing its laterally extending arm over the walk, and, in its lowered position, 5 to bring its lateral arm adjacent to the side wall of the cellar where it will not interfere with the free use of the opening into the cellar for other purposes. As the hoisting member and its support turn together, 10 this turning movement for changing the position of the laterally extending arm brings no additional strain upon the pin which supports the hoisting member in its raised position.

15 I claim as my invention:

1. In a hoisting apparatus, the combination of a supporting member having a pulley journaled in one side thereof near its upper end, a hoisting member having tele- 20 scopic engagement with said supporting member, and having an open slot extending longitudinally in the side thereof adjacent to said pulley and through which said pulley projects, elevating means for said 25 hoisting member, a flexible connection be- 30 tween said elevating means and said hoisting member which passes over said pulley and through said slot and downwardly within said hoisting member to the lower end 35 portion thereof where it is secured thereto, means for securing the hoisting member in its elevated position, hoisting means carried by said hoisting member, and means for securing said supporting member in an up- 40 right position, substantially as set forth.

2. In a hoisting apparatus, the combination of a supporting member having a pulley journaled in one side thereof near its upper end, a hoisting member having tele- 45 scopic engagement with said supporting member, and having an open slot extending longitudinally in the side thereof adjacent to said pulley, through which said pulley extends, elevating means for said hoisting member, a flexible connection between said elevating means and said hoisting member which passes over said pulley and through said slot and downwardly within said hoisting member to the lower end portion thereof 50 where it is secured thereto, a laterally ex- 55 tends arm carried by said hoisting member and having an open slot extending longitudinally thereof on its under side, a pulley arranged in said slot at the outer end 60 of said arm and journaled in the sides thereof, a flexible hoisting member which passes over said pulley and through said slot, means for operating said member, and means for securing said supporting member 65 in an upright position, substantially as set forth.

3. In a hoisting apparatus, the combination of a supporting member of substan-

tially channel shape, a hoisting member ar- 65 ranged in the channel portion of said sup- porting member and having laterally ex- 70 tends flanges, guide-ways on said sup- porting member for said flanges, elevating means for raising said hoisting member to an elevated position, hoisting means car- 75 ried by said hoisting member, and means for securing said supporting member in an up- right position, substantially as set forth.

4. In a hoisting apparatus, the combina- 80 tion of a supporting member of substan- 85 tially channel shape, a hoisting member ar- 90 ranged in the channel portion of said sup- porting member and having laterally ex- 95 tends flanges and an open slot which ex- tends longitudinally thereof between said flanges, guide-ways on said supporting member for said flanges, elevating means secured to said hoisting member in said slot for raising said member to an elevated po- 100 sition, hoisting means carried by said hoist- 105 ing member, and means for securing said supporting member in an upright position, substantially as set forth.

5. In a hoisting apparatus, the combina- 90 tion of a supporting member of substan- 95 tially channel shape, a hoisting member ar- 100 ranged in the channel portion of said sup- porting member and comprising angle bars having laterally extending flanges and par- 105 allel spaced flanges, guide-ways on said sup- 110 porting member for said laterally extending flanges, elevating means arranged between said spaced flanges for raising said hoisting member to an elevated position, hoisting means carried by said hoisting member, and 115 means for securing said supporting member in an upright position, substantially as set forth.

6. In a hoisting apparatus, the combina- 105 tion of a supporting member of substan- 110 tially channel shape, a hoisting member ar- 115 ranged in the channel portion of said sup- porting member and comprising angle bars having laterally extending flanges and par- 120 allel spaced flanges, guide-ways on said sup- 125 porting member for said laterally extending flanges, elevating means arranged be- 130 tween said spaced flanges for raising said hoisting member to an elevated position, hoisting means carried by said hoisting member, and pivotal means for securing said supporting member in an upright position which permit it to turn in a horizontal direction, substantially as set forth.

7. In a hoisting apparatus, the combina- 120 tion of a supporting member of substan- 125 tially channel shape, a hoisting member ar- 130 ranged in the channel portion of said sup- porting member and comprising angle bars having laterally extending flanges and par- 135 allel spaced flanges, guide-ways on said sup-

porting member for said laterally extending flanges, elevating means arranged between said spaced flanges for raising said hoisting member to an elevated position, a laterally extending arm carried by said hoisting member and comprising spaced angle bars which are secured thereto, hoisting means arranged in the space between the said angle bars of said arm, and means for securing

10 said supporting member in an upright position, substantially as set forth.

Witness my hand, this 9th day of March, 1911.

CHARLES K. ERNST.
